Attorney

UNITED STATES PATENT OFFICE.

LENA GRUNER, OF INDIANAPOLIS, INDIANA.

HOSE PROTECTOR.

Application filed March 3, 1927. Serial No. 172,498.

My invention relates to hose protectors and it is an object of the invention to provide a device of this character adapted to be applied on the inside of the top of arctics or 5 galoshes, either high or low to prevent the hose of the wearer from being soiled by the top of the galosh rubbing against the same.

Referring to the accompanying drawings, which are made a part hereof and on which 10 similar reference characters indicate similar parts,

Figure 1 is a plan view of the pattern or blank,

Figure 2, shows the manner of applying 15 the same to the ankle or leg,

Figure 3, a view illustrating the same in position with a galosh applied, and

Figure 4, a similar view illustrating the 20 manner in which the same is adapted to be worn.

In the drawings reference character 10 indicates an elongated body or blank preferably of knitted, woven or other desired fabric having a soft finish and which will not 25 be uncomfortable to the wearer. The device is designed to be used by ladies and is adapted to be wrapped around the ankle or leg in a position so that the top of an arctic, galosh or other overshoe will extend 30 substantially midway of the same and protect silk, chiffon or other hose from being soiled by the rough surface of the galosh.

A fabric of the above description will conform to the tapered surface to which it is 35 applied, however, I preferably cut out the middle portion of both sides of the material, the upper portion being provided with a curved edge 11 and the lower edge being provided with an upper curved edge 12, said 40 curved edges being disposed at the back of the leg so that the article more closely conforms thereto. Each end of the elongated body has its corners cut out and is provided with arcuate edges 13 at the upper 45 side and with arcuate edges 14 at the lower

side, such arcuated edges defining the tongue 15 at each end of the body. I preferably stitch or otherwise form the fabric around its edges to prevent unraveling of the fabric and in order to cause the same to maintain 50 its shape.

When the article is applied the tongues 15 are disposed at the front of the leg and overlap, as shown in Figure 2 and on account 55 of their relatively narrow construction they permit the body to conform snugly to the ankle or leg without wrinkling and also permit the upper portion of the body to fold outwardly and downwardly over the top of the galosh in an artistic manner to form a 60 cuff. On account of the unique pattern and texture of the fabric it will remain in place without any fastening means and presents a very neat appearance as well and is quite serviceable for protecting the hose. 65

It will be obvious to those skilled in the art that various changes may be made in my device without departing from the spirit of the invention and therefore I do not limit myself to what is shown in the drawings 70 and described in the specification but only as indicated in the appended claim.

Having thus fully described my said invention, what I claim as new and desire to 75 secure by Letters Patent, is:

A hose protector comprising a body of flexible material adapted to be applied about the leg and extend downwardly into the top of a shoe and arranged to fold over the top of the shoe and form a cuff, the said body being of length sufficient to extend around the leg and overlap and having also inwardly curved edges at its upper and lower sides adapted to conform to the leg of the wearer, 80 substantially as set forth. 85

In witness whereof, I have hereunto set my hand at Indianapolis, Indiana, this 28th day of February, A. D. nineteen hundred and twenty-seven.

LENA GRUNER.
